(57) **CLAIM**

The ornamental design for a door handle, as shown and described.

DESCRIPTION

FIG. 1 is a perspective view of a door handle;

FIG. 2 is a bottom view of FIG. 1;

FIG. 3 is a top view of FIG. 1;

FIG. 4 is a rear view of FIG. 1;

FIG. 5 is a front view of FIG. 1;

FIG. 6 is a left side view of FIG. 1; and,

FIG. 7 is a right side view of FIG. 1.

The design is intended to be used in connection with a door handle for a vehicle. Exemplary attachment mechanisms are shown in hidden lines in the various Figures.

1 Claim, 2 Drawing Sheets

FIG. 4

FIG. 3

FIG. 5
